UNITED STATES PATENT OFFICE.

JOHN H. CLARK, OF BOSTON, MASSACHUSETTS, ASSIGNOR TO THE WHITTIER MACHINE COMPANY, OF SAME PLACE.

ELEVATOR MECHANISM.

SPECIFICATION forming part of Letters Patent No. 573,809, dated December 22, 1896.

Application filed July 28, 1890. Serial No. 360,162. (No model.)

To all whom it may concern:

Be it known that I, JOHN H. CLARK, of Boston, county of Suffolk, State of Massachusetts, have invented an Improvement in 5 Elevator Mechanism, of which the following description, in connection with the accompanying drawings, is a specification, like letters on the drawings representing like parts.

This invention relates to elevator mechanism of that class in which an electric motor is used to furnish the power employed to actuate the elevator.

My invention consists in the features of construction and arrangement of parts having the mode of operation substantially as hereinafter set forth.

Figure 1 is a side elevation of one end of an elevator-operating mechanism embodying my invention; Fig. 2, a top or plan view of a 20 portion of the elevator mechanism shown in Fig. 1, together with additional parts; Fig. 3, a side elevation of the other portion or end of the machine from that shown in Fig. 1, looking on the opposite side; and Fig. 4, a 25 diagram of circuits to more clearly illustrate the operation of the mechanism.

The electric motor A has its armature-shaft a³ supported by uprights a⁴ a⁵ and, as herein shown, connected to a worm-shaft a¹⁰ by 30 an independent coupling, (shown as flanged hubs a⁸ a⁹,) fast on the armature-shaft a³ and on the worm-shaft a¹⁰, respectively, the flanges a⁶ a⁷ of the said hubs being secured together, as by bolts a⁸.

35 The worm-shaft a¹⁰, as herein shown, has bearings in a case or frame a¹², and is provided with two worms a¹³ a¹⁴, (represented by dotted lines, Fig. 3,) the said worms engaging worm-gears a¹⁵ a¹⁶, mounted on shafts a¹⁷ 40 a¹⁸, having bearings in the sides of the case a¹², the said worm-gears meshing with each other.

In practice one of the shafts a¹⁷ a¹⁸ may have mounted upon it one or more drums a²⁵, 45 only one of which is shown in Fig. 3, upon which the hoisting cable or cables a³⁰ may be wound to raise the elevator-car, as in the ordinary drum-elevator, or the said shafts may be connected in suitable manner to drive a 50 pump usually employed in the hydraulic-elevator system.

The shaft a¹⁷ of the worm-gear a¹⁵ is extended outside of the case a¹², and is provided with screw-threads b, which engage screw-threads on the inner circumference of the hub of a gear-wheel b', provided on one side with a projection or tooth b², adapted to engage a projection b⁴ (see dotted lines, Fig. 2) on a wheel b⁵, fast on the shaft a¹⁷, and provided on its opposite side with a tooth b³ 60 to engage a tooth b⁶ on a hub b⁷, fastened to the said shaft, as by a key b⁸.

The gear b' meshes with a substantially wide gear b⁹, loose on a stud b¹⁰, herein shown as secured to the side of the case a¹², and the 65 loose gear b⁹ engages with a gear b¹² on a shaft b¹³, upon which is mounted, as herein shown, the usual shipper wheel or pulley b¹⁴.

The wheel b⁵ and hub b⁷, provided with the teeth b⁴ b⁶, the pinion b', having the teeth b² 70 b³, and the gears b⁹ b¹² constitute one form of automatic stop mechanism for the elevator mechanism.

The shaft b¹³, as herein represented, is extended through a suitable sleeve or hub b¹⁵, 75 which is fast upon the said shaft, and which is provided at the opposite side of the machine (see Fig. 1) with a disk b¹⁶, eccentrically mounted on the shaft b¹³, or upon a reduced portion thereof c, the said eccentric disk being provided with an eccentric-strap b¹⁷, to which is connected the movable member of a circuit-controlling device, preferably a pole-changer, herein shown as consisting of terminal plates or brushes b¹⁸ b¹⁹ b²⁰, secured to 85 a suitable base b²¹, preferably of insulating material.

The terminal plates or brushes have co-operating with them two contact bars or brushes b²² b²³, herein shown as secured to a 90 bar or rod b²⁴ of insulating material, pivoted at b²⁵ to a projection or stud on the eccentric-strap b¹⁷, the said contact-brushes, as herein represented, being secured at their rear end to bars b²⁶ b²⁷, pivoted to the base b²¹.

The reduced portion c of the shaft b¹³, on 95 which the eccentric disk b¹⁶ is mounted, has a crank or arm c', to which is pivoted, as herein shown, a rod c², provided at its lower end with a rack-bar c³, having secured to or 100 forming part of it, as herein shown, a bar c⁶, provided with a slot into which is extended

the shaft c^x of a pinion c^4 in mesh with said rack-bar, and which is rotated by the movement of the rack-bar, produced by the revolution of the shaft c , the bar c^6 in its movement tipping or rocking on the shaft c^x .

The shaft c^x of the pinion c^4 has mounted on it one end of an arm or lever c^7 , having secured to or forming part of its opposite end a contact-brush c^8 , forming one member of a switch, the coöperating member of which consists of a series of resistances c^9 , arranged in the arc of a circle and supported by a suitable frame c^{10} .

The lever c^7 in practice has connected to it a wire c^{12} , (see Fig. 4,) joined to one commutator-brush, as a' , of the electric motor A, and the lowest resistance of the series of resistances c^9 has connected to it a wire c^{13} . (See Fig. 4.)

The sleeve or hub b^{15} has secured to or forming part of it, as herein shown, an annular ring b^{30} , (see Fig. 2,) provided with a lug or ear b^{31} , adapted to be brought into engagement with a lug or projection b^{32} on the side of the case a^{12} by a partial rotation of the shaft b^{13} and the sleeve b^{15} , fast thereon. The lug b^{31} , when brought into engagement with the stud b^{32} by the partial rotation of the shaft b^{13} in one direction, as indicated by arrow 50, Fig. 2, stops the rotation of the said shaft in that direction and thereby limits the movement of the rack-bar c^3 in the direction indicated by arrow 40, Fig. 1, the contact-brush c^8 at such time being disengaged from the resistances c^{10} , and the circuit of the electric motor being broken. When the lug b^{31} is brought into engagement with the stud b^{32} in the partial rotation of the shaft b^{13} in the direction opposite to that indicated by arrow 50, the said shaft is stopped in its rotation, the contact-brush c^8 being at such time in engagement with the lowest resistance c^9 , and the motor is being run with a maximum amount of current.

The elevator mechanism herein shown is provided with an electric brake mechanism consisting of a brake-wheel d , herein shown as mounted on the hub a^6 , the said brake-wheel being encircled by a brake-strap d' , having its ends secured in suitable manner to a hub d^2 , fast on a rock-shaft d^3 , having suitable bearings in the framework of the machine, the said hub having secured to or forming part of it a lever d^4 , which in practice is provided with a counterbalancing-weight d^5 . (See Fig. 1.) The rock-shaft d^3 has also fast upon it, as herein shown, a hub d^6 , having an arm d^7 , to which is secured a link d^8 , fastened, as by a pin d^9 , to a bar d^{10} , having secured to or forming part of it cores d^{12} of a solenoid d^{13} , which may be of any usual or well-known construction, the said solenoid having one of its wires, as d^{14} , connected to the commutator-brush a^2 and its other wire d^{15} joined to the terminal b^{19} of the pole-changer, as shown in Fig. 4.

The brake-strap d' is secured to the hub d^2

in such manner that when the solenoid d^{13} is energized and its cores d^{12} are attracted within it the rock-shaft d^3 is turned so as to release 70 the brake-strap from the brake-wheel d and permit of the free rotation of the said brake-wheel; but when the circuit of the solenoid d^{13} is broken the counterbalancing-weight d^5 will turn the rock-shaft d^3 , so as to cause the 75 brake-strap to bind upon the brake-wheel d and hold it stationary, thereby preventing rotation of the worm-shaft and of the armature-shaft of the motor.

Referring to Fig. 4, the pole b^{18} of the pole-changer is connected by wire e to the pole b^{20} . The contact brush or arm b^{22} of the pole-changer has connected to it one wire e^2 of the armature-circuit of the motor, which wire is shown in Fig. 4 as being connected to the 85 negative line-wire e^{20} , and the other contact-arm b^{23} of the pole-changer has connected to it the other wire e^3 of the armature-circuit, which wire in turn is connected with the positive line-wire e^{21} , the said positive and negative line-wires being connected to the field-magnet of the electric motor. The resistance device c^9 is in the armature-circuit, and its lower end is joined to the terminal b^{20} of the pole-changer by the wires c^{13} .

In operation the elevator mechanism is started when the contact-brush c^8 on the switch-lever c^7 is brought into contact with the first of the resistances c^9 . This may be accomplished by turning the shipper-wheel b^{14} by 100 means of the usual shipper-rope operated from the car, or by any other usual or well-known form of starting and stopping mechanism operated from the said car. When the shipper-wheel b^{14} is rotated so as to bring the 105 contact-brush c^8 in contact with the resistances c^9 , the pole-changing arms $b^{22} b^{23}$ are brought in contact with the poles $b^{18} b^{19}$ and the circuit of the electric motor is completed, which circuit may be traced as follows, viz: 110 through the positive wire e^{21} , field-magnets, to the negative wire e^{20} , thus completing the circuit through the field-magnets of the motor. A portion of the current flows from the positive wire e^{21} , wire e^3 , contact-brush b^{23} , 115 terminal b^{19} , wire d^{15} , solenoid-coils d^{12} , wire d^{14} , commutator-brush a^2 , armature of the motor, brush a' , wire c^{12} , lever c^7 , resistances c^9 , wire c^{13} , terminal b^{20} , wire e , terminal b^{18} , brush b^{22} , and wire e^2 to negative wire e^{20} . 120 The rotation of the armature-shaft and of the worm-shaft is automatically stopped, as described, when the lug b^{31} is brought into engagement with the stud b^{32} , which occurs when one of the teeth $b^2 b^3$ on the gear or pinion b^1 engages with one of the projections b^4 b^6 , the shaft b^{13} being given a partial rotation sufficient to disengage the pole-changing arms $b^{22} b^{23}$ from its coöperating poles, but if it is desired to stop the elevator positively by hand 125 the operator may move the shipper-wheel b^{14} in the direction opposite to that indicated by arrow 20, Fig. 1, and thus move the rack-bar c^3 in the direction of arrow 40 to cause the

pinion c^4 to rotate and move the switch-lever c^7 back, and thus withdraw the contact-brush c^8 from engagement with the resistances c^9 .

If it is desired to rotate the armature of the electric motor in the direction opposite to that in which it is rotated when the contact-arms $b^{22} b^{23}$ of the pole-changer are in contact with the poles $b^{18} b^{19}$, the shipper mechanism is rotated in the direction opposite to that indicated by arrow 20 until the contact-arms $b^{22} b^{23}$ of the pole-changer are brought in contact with the poles $b^{19} b^{20}$, at which time the circuit of the electric motor is completed at the pole-changer and through the resistances, the circuit through the field-magnets of the motor being the same as described, and the circuit through the armature being as follows, viz: wire e^3 , contact-arm b^{23} , pole b^{20} , wire c^{13} , resistances c^9 , lever c^7 , wire c^{12} , commutator-brush a' , armature, commutator-brush a^2 , wire d^{14} , coils d^{12} of solenoid, wire d^{15} , pole b^{19} , contact-arm b^{22} , and wire e^2 .

It will be thus seen that the motor A is a shunt-motor and that the resistance device and the pole-changer are located in the armature-circuit of the motor. This arrangement is of great advantage and importance in an elevator apparatus, because thereby it is possible to run the elevator-car at all times at a uniform speed, whether running up or down and with or without a load.

In order that the shaft b^{13} may be rotated in opposite directions to automatically break or open the circuit of the motor and thus stop the elevator when it has reached the limit of its travel in either direction, the gear b' is provided with the teeth $b^2 b^3$ to engage the teeth $b^4 b^6$.

When the tooth b^3 engages the tooth b^6 , the shaft b^{13} is rotated in the direction of arrow 20, Figs. 1 and 3, until the eccentric disk b^{16} occupies a position substantially diametrically opposite from the position shown in Fig. 1, and when the tooth b^2 engages the tooth b^4 the shaft b^{13} is rotated in a direction opposite to that indicated by arrow 20 and the eccentric disk brought into the position shown in Fig. 1, thus opening the electric circuit.

I do not in this application claim a circuit-controlling device containing a circuit-reverser and a current-regulator having a regulating member, in combination with operating means for the circuit-reverser and current-regulator, by means of which, when the parts are moved to effect a change of polarity of

the current, the movement of the regulating member is in the same direction, as I have made this the subject-matter of another application, which I have filed, bearing Serial No. 419,625.

I claim—

1. In an elevator mechanism, the combination of the following instrumentalities, viz: two worm-gears in mesh with each other, one of the said gears having its shaft provided with screw-threads, a worm-shaft having worms in engagement with the said worm-gears, an electric motor, its armature, an independent coupling connecting the said armature-shaft directly to the worm-shaft, a resistance in circuit with the motor, a lever coöperating with said resistance, a shaft b^{13} provided with an eccentric, a rack-bar connected to the said eccentric, a pinion in mesh with said rack-bar and to which the resistance-lever is connected, gearing to connect the screw-threaded worm-gear shaft with the shaft b^{13} , an electric brake mechanism, and a pole-changer in circuit with the motor and brake mechanism, substantially as described. 60

2. In an elevator mechanism, the combination of the following instrumentalities, viz:

two worm-gears in mesh with each other, one of the said gears having its shaft provided with screw-threads, a worm-shaft having worms in engagement with the said worm-gears, an electric motor, its armature, an independent coupling connecting the said armature-shaft directly to the worm-shaft, a resistance in circuit with the motor, a lever coöperating with said resistance, a shaft b^{13} provided with an eccentric, a rack-bar connected to the said eccentric, a pinion in mesh with said rack-bar and to which the resistance-lever is connected, gearing to connect the screw-threaded worm-gear shaft with the shaft b^{13} , an electric brake mechanism consisting of a brake-wheel d , a brake-strap, a hub to which the said brake-strap is connected, an electromagnet having its armature 85 connected to said hub, and a pole-changer in circuit with the said electromagnet and motor, substantially as described. 80

In testimony whereof I have signed my name to this specification in the presence of 105 two subscribing witnesses.

JOHN H. CLARK.
